RAILWAY-TIE.

1,105,718.

Specification of Letters Patent.

Patented Aug. 4, 1914.

Application filed June 25, 1907. Serial No. 380,648.

To all whom it may concern:

Be it known that we, WILLIAM P. THOMSON and SAMUEL G. THOMSON, residents of the city and county of Philadelphia, State 5 of Pennsylvania, have invented an Improvement in Railway-Ties, of which the following is a specification.

Our invention relates to that class of railway ties which are made up of metal and 10 wooden members, and consists essentially of a tie having a central and outer metal members with intermediate wooden members between the central and outer members at the rail bearings. This form of tie is particularly 15 adapted to those conditions of road-bed and traffic which require very stiff and heavy rail bearings, and especially to those conditions which require great vertical stiffness throughout the tie. This vertical stiffness can be secured by extending all three 20 of the metallic members the full length of the tie under the rails. In those cases, however, where such great vertical stiffness is not required throughout the entire length 25 of the tie, the central portions of one or more of the metal members may be omitted, without affecting the stiffness and strength 30 of the rail bearings. Aside from the greater stiffness imparted to the tie—whether it be throughout its length, or at the rail bearings 35 only—the outer metal members, when combined with the central metal member and the intermediate wooden blocks, have the effect 40 of providing a wider and better bearing surface for the rails than could be obtained either by wood or metal alone. The metal members, while presenting a greater metal surface to receive the shocks, transmit such shocks to the wooden members and thus 45 preserve the elasticity of a wooden tie while protecting the wood from injury by the direct shocks; and by using outer members of the proper form the increased area of the metal surface to receive the direct shocks 50 and the protection of the wooden blocks from such shocks may be regulated to suit the engineering conditions and the character of the traffic. The construction also permits narrower wooden blocks to be used, to provide 55 the desired elasticity and efficient spiking facilities, than would otherwise be possible.

In the drawings: Figure 1 is a plan view of a railway tie embodying the invention 55 and illustrating one of the forms with the

metal members of the sections shown in Fig. 4; Fig. 2 is a similar view illustrating another form with the metal members of the sections shown in Fig. 9; Fig. 3 is a similar view illustrating still another form with the 60 comparatively shallow metal members of the sections shown in Fig. 8; and Figs. 4, 5, 6, 7, 8 and 9 are transverse sections of the tie at or adjacent to the rail bearing portion 65 thereof, Figs. 4, 9 and 8 being taken respectively on the lines A—A of Fig. 1, B—B of Fig. 2 and C—C of Fig. 3 on an enlarged scale.

a a' are the metal members of the tie, 70 one or more of which is of a length sufficient to extend under both rails; these members may be of any cross section, but we prefer to employ structural irons, the particular section employed depending on the character of the road-bed and other engineering conditions. The central metal member is designated as *a* and the outer members as *a'* and *a''*. In some cases, as in the construction shown in Fig. 1, all three members *a a' a''* will extend from rail to rail; 80 in others, as in Fig. 2, the outer members *a'* *a''* only, and in others, as in Fig. 3, the central member *a* only.

b b are the wooden portions or members, 85 which, as shown, consist of wooden blocks secured between the central member *a* and the outer members *a' a''* at the rail bearings.

In the plan view shown in Fig. 1 each of the metal members *a a' a''* extends the whole length of the tie under the rails *c c*, 90 and said members are of unequal depths as shown by the sections in Fig. 4. The wooden blocks or members are secured between the central member *a* and the outer members *a' a''* by any suitable means, as by bolts *c' c''*, as 95 shown in Figs. 4, 5 and 6, or by rivets *c''*, as shown in Figs. 7, 8 and 9. In this particular form shown in Figs. 1 and 4 the central member *a* is an I bar and the outer members *a' a''* are comparatively shallow angle irons, with their flanges *a''* turned inward, the flange of the central member *a* and the flanges *a''* of the outer members *a' a''* thus present and extended metal bearing surface for the rails *c c* and fully protect the 105 wooden blocks *b b* from the direct shocks and consequent wear. It will also be noted that these flanges extend over the outer portions of the wooden block, leaving the central portion only exposed to receive the 110

spikes c' , so that the driving of the spikes into the body of the blocks is assured. Substantially the same results are obtained with the sections shown in Figs. 5, 6 and 9.

5 In Figs. 7 and 8 the wooden blocks are shown with their upper faces extending above the upper faces of the metal members. Such forms are especially suited to those conditions where an all wooden rail bearing

10 is desired, but, even in such cases, it will be noted that the wood is confined on both sides by metal and that there will be less danger of splitting the blocks by the spikes than would otherwise be the case. In any case

15 narrower blocks may be employed for imparting elasticity and affording fastening facilities than would otherwise be possible.

In the form shown in Figs. 2 and 9, the outer members a' a^2 extend from rail to rail 20 and the central member—shown as a flat plate—extends between the blocks b b under the rail bearings only.

In the form shown in Figs. 3 and 8, the central member a is a T bar extending from 25 rail to rail and the outer members a' a^2 extend the length of the blocks b b only and have their flanges a^3 turned outwardly.

While we have shown separate wooden blocks b extending under the rail bearings 30 only, continuous wooden pieces extending from rail to rail may be employed, if desired, but ordinarily that is not desirable, particularly in those constructions in which two or all of the metal members extend 35 from rail to rail, as in the constructions shown in Figs. 1 and 2, as in such cases the open space between the metal members forms a pocket to receive ballast or the material of the road-bed.

40 It is important to note that the outer metallic members may be made shallower than the blocks in the manner shown in Figs. 4 and 8; thus a portion of the outer sides of the blocks may be exposed to the ballast of

45 the road-bed to compensate for as much of the bottom of the blocks as may be separated from the ballast by the bottom flanges of the central metallic member. This construction also greatly facilitates tamping

50 under the rail bearing portions of the ties and renders the tie less liable to cut into the tamped road-bed than would be the case if sharp metallic edges were exposed to the roadbed. It is also particularly important

55 to note that the metallic members which extend under one rail only may be so disposed with reference to the separating wooden blocks that they will be the only metallic members of the structure which bear against

60 the rails and that by keeping them and all clamping and fastening means entirely free from contact with the metallic member or members which extend under both rails, a

65 complete insulation of one rail from the other is secured; the use of comparatively

shallow sections for the rail bearing members, which are insulated from each other, affords still further protection against electrical connection between these rail bearing members because their shallowness keeps 70 them above such accumulated water or wet substance in the road-bed as would establish electrical connection between the rail bearing members.

When we speak of the "blocks" or intermediate members between the metal members a a' a^2 as "wooden" members, it is to be understood that we mean to include a block or member composed of other suitable material or composition which may be used 80 as a spiking or rail fastening member or as an elastic rail bearing.

For the purpose of holding the wooden blocks more firmly in place the web of one or more of the metallic members may be 85 provided with spurs, projections or irregularities adapted to bite into or engage the faces of the blocks, as shown at e in Figs. 4 and 5.

What we claim is as follows:

1. A railway tie having rail bearing portions consisting of a plurality of metallic members and interposed blocks secured to them, one of said metallic members between two of said blocks extending a substantial 95 distance below an outer metallic member, said outer metallic member having a lateral flange.

2. A railway tie consisting of a central metallic member, blocks located on each side 100 of said central member, outer metallic members fitting the upright outer faces of said blocks, said central metallic member extending a substantial distance below said outer metallic members, and means for holding 105 said parts together.

3. A railway tie consisting of a central metallic member, blocks located on each side of said central member at the rail bearings, outer metallic members, having lateral 110 flanges, arranged on the outer faces of said blocks and having their lowermost edges lying a substantial distance above the bottom of said blocks, and means for holding said parts together.

4. A railway tie consisting of a central metallic member, blocks located on each side of said central member at the rail bearings, outer metallic members, having lateral 120 flanges, arranged on the outer faces of said blocks and having their lowermost edges lying a substantial distance above the bottom face of said central member, and means for securing said parts together.

5. A railway tie consisting of a central 125 metallic member, blocks located on each side of said central member at the rail bearings, outer metallic members standing entirely free from said central member and each outer member being less in height than is the 130

outer face of the block against which it bears, one of said metallic members having a horizontal flange extending along its top.

6. A tie consisting of three metallic members at each end and one of which extends under both rails, said members being entirely separated from each other by intervening blocks, one of said metallic members which bears on one side of one of said blocks being substantially less in depth than is the other of said metallic members which bears on the opposite side of the same block.

7. A tie having a plurality of metal plates spaced equidistant throughout their length with interposed blocks extending above them to form insulated rail bearings, one of said plates being of less depth than the interposed blocks and also of less depth than an-

other of said metal plates, and means for holding said parts together. 20

8. A railway tie consisting of a central metallic member, blocks located on each side of said central member, outer metallic members arranged on the outer faces of said blocks, said central metallic member being 25 relatively deeper than the outer metallic members, and means for holding said parts together.

In testimony of which invention, we have hereunto set our hands.

W. P. THOMSON.
